UNITED STATES PATENT OFFICE

ADAM M. COX, OF LYNCHBURG, VIRGINIA, ASSIGNOR TO LYNCHBURG HOSIERY MILLS,
OF LYNCHBURG, VIRGINIA, A CORPORATION OF VIRGINIA

KNITTING MACHINE

Application filed December 3, 1929. Serial No. 411,302.

My said invention relates to knitting machines and specifically to a device for making patterns in hosiery. It is an object of my invention to provide improved striping means for making narrow vertical stripes in fabrics formed on a circular independent needle knitting machine.

Another object of my invention is to provide an improved cam set for cooperation with needles to be selectively elevated, or left selectively in elevated position, for the purpose of taking striping or pattern yarns from yarn guides which preferably are at a higher elevation than the other yarn guides.

15 Referring to the drawing, which is made a part of this application and in which similar reference characters indicate similar parts,

Fig. 1 is a partial vertical section of a machine embodying my improvements,

Fig. 2, an elevation of the cam ring, partly in section,

Fig. 3, a fragmentary inner elevation of the cam ring and yarn guides,

25 Fig. 4, an elevation of the cam set, showing the top center cam in a different position from that of Fig. 3, and

Fig. 5, a detail showing specimens of the needles employed.

30 In the drawing reference character 10 indicates a needle cylinder which may be of any desirable or conventional form and which has needle slots as usual in which needles 11 are positioned for up and down movement. The sinker ring 12, the sinkers 13, the yarn guide operating bars 14 and other parts not hereinafter specifically described may all be of conventional or desirable type.

The main yarn guides 15 (which term is 40 herein used to designate any of the guides except those for the special pattern yarns) may be of conventional form and may be operated in conventional manner through the bars 14 under control of pattern mechanism of 45 conventional type, but the pattern yarn guides 16 and 17 preferably have openings at their ends as indicated at 18, through which the pattern yarns are led instead of passing through to the bottom of the yarn 50 guides and preferably these openings 18 are

formed in small extensions of the pattern yarn guides, as clearly indicated in Fig. 1, thereby to feed the pattern yarns close to the needles and under the hooks of the same. Preferably also the pattern yarn guides are 55 held in more elevated position at their outer ends than are the main yarn guides and for this purpose I provide adjusting screws as indicated at 20 in the yarn guide bracket 21. The adjusting screws are held in position by 60 set screws 22. As clearly shown in Fig. 3 this makes the normally lowered position of the pattern yarn guides somewhat higher than that of the yarn guides 15.

The cam set comprises stitch cams 23 and 65 24, bottom center cam 25 and top center cam 26 and a fixed needle separating cam 27. The top center cam, as best shown in Fig. 2, is mounted on a standard 28 having a horizontal slot at 29 and the cam is held in place by 70 a pair of screws 30 in such a manner as to permit the cam to move circumferentially of the cam ring to an extent illustrated by comparison of Figs. 3 and 4. In the one position it may somewhat overlap cam 27 and 75 in the other position it approaches rather closely to cam 23.

The needle separating cam 27 is interposed substantially between top center cam 26 and stitch cam 24 for the purpose of separating 80 the needles. Needles of three varieties are used in the machine, these needles comprising long butt needles 31 in a half circle extending over approximately one-half of the circumference of the needle cylinder, these 85 needles being those idled during the operation of making heels and toes and being designated as instep needles. Needles 32 with medium butts are those of the other half of the set, on which heels and toes are knitted to by oscillation in ordinary manner. Inter- 90 spersed among the needles of both the other sets are short butt needles 33 and these needles may be positioned at intervals about the needle cylinder in such number as de- 95 sired. For making a particular pattern the short butt needles in the present instance are shown as occurring in pairs with a long butt needle between them, as in Fig. 3, but any other arrangement may be made as the pat- 100

tern requires. By this arrangement, and in the absence of other controlling factors, longitudinal stripes will be made in the fabric, the length of such stripes being in this instance controlled by putting pattern yarn guides into and out of action.

To provide room for the cam 27 the stitch cam 24 is somewhat reduced adjacent the cam 27. The stitch cam 23 is also reduced somewhat, as compared with conventional stitch cams, so as to provide space for the needles to pass between it and top center cam 26 in making reciprocating work. The upper face of bottom center cam 25 is also reduced somewhat, particularly at the right hand end of the same. In Fig. 3 the top center cam is shown as having slid to the left so far as permitted by the slot 29 and the left hand screw 30. The long butt and medium butt needles will engage the active face of cam 27 as they pass from stitch cam 24 and will be carried down to a level below the lower end of said cam. When they now engage cam 26 they will be carried still lower to a level where they can engage stitch cam 23 and draw their stitches. The butts of the short butt needles are so short however that they will not engage cam 27 but will pass across its face until they reach cam 26, whereupon they will be carried down to the bottom of the cam so as to engage stitch cam 23 and draw their stitches. In this manner the short butt needles are left at such an elevation as to travel along the path indicated at 35 in Fig. 3 whereas the medium butt and short butt needles pass along the path indicated at 36 and therefore the short butt needles will take the yarn from pattern yarn guides 16 and 17 but all the needles will take the main yarn fed from any one of the guides 15. It is desirable to have the cam 26 spaced laterally to some small extent from cam 27 in knitting the patterned portion of the stocking but if the cam 26 were permanently located in the position indicated in Figure 3 there would not be enough room between it and cam 23 for the needles to pass in heel and toe knitting. In order therefore that the cam 26 may be able to assume substantially a central position between cams 23 and 24 for heel and toe knitting (but an offset position during knitting of the patterned portion, i. e., usually the leg or a part of the leg), I have mounted the cam 26 for free lateral movement. By thus leaving the cam free to move laterally I do away with various pattern devices heretofore used for obtaining similar results with the aid of needle operating cams or the like and secure my result with very simple mechanism.

For the purpose of leveling all the needles in reciprocating or oscillating knitting a pair of cams are provided as indicated at 37 and 38, it being found that in the absence of these cams some of the needles are liable to ride

too high and strike the cams 26 and 27 above their cam faces.

It will be obvious to those skilled in the art that many variations may be made in the construction shown in the accompanying drawing and described in the specification and therefore I do not limit myself to any features of the specific disclosure but only as indicated in the appended claim.

Having thus fully described my said invention, what I claim as new and desire to secure by Letters Patent is:

In an independent needle hosiery knitting machine, a slotted needle cylinder, needles in slots of the needle cylinder including a series of long-butt needles at one side of the needle cylinder, a series of medium-butt needles at the other side and short-butt needles intercalated among the needles of said series; means for guiding a main or body yarn to the needles and for guiding a pattern yarn thereto at a point higher up than the main yarn and in advance thereof; and a needle-actuating cam set including stitch-cams, a top center cam, and a cam for lowering the long-butt and medium-butt needles before they pass the yarn guiding means to a level where they take only the main or body yarn, said top center cam being mounted for circumferential sliding movement relatively to the needle circle, as and for the purposes set forth.

In testimony whereof I affix my signature.

ADAM M. COX.
